Attorney

UNITED STATES PATENT OFFICE.

PATSY FASSON, OF MOUNT PLEASANT, PENNSYLVANIA.

ROLLER WINDOW SCREEN.

Application filed March 6, 1923. Serial No. 623,266.

To all whom it may concern:

Be it known that I, PATSY FASSON, a citizen of the United States, residing at Mount Pleasant, in the county of Westmoreland 5 and State of Pennsylvania, have invented certain new and useful Improvements in Roller Window Screens; and I do hereby declare the following to be a full, clear, and exact description of the invention, such as 10 will enable others skilled in the art to which it appertains to make and use the same.

This invention relates to a roller window screen.

It is aimed to provide a novel construction utilizing a casing applicable in upstanding position adjacent one of the stiles of the window frame and between the sill and lower sash thereof, adapted to contain a horizontally movable screen, together with 15 means on the casing and adjacent the free end of the screen to penetrate said sill and sash and thereby temporarily maintain the screen in operative position.

Another object is to provide a novel closure plate carried by the sash to coact with the upper edge of the screen, which plate is 20 movably mounted so that it will permit closing of the sash without requiring its detachment therefrom.

A third object is to provide a novel spring 25 control and tensioning means for the screen.

Additional objects and advantages will 30 become apparent from a consideration of the description following taken in connection 35 with accompanying drawings illustrating an operative embodiment.

In said drawings:—

Figure 1 is a view in front elevation showing the screen in operative position applied to a window frame fragmentarily illustrated;

Figure 2 is a vertical sectional view on the line 2—2 of Figure 1;

Figure 3 is an enlarged elevation of the device alone, partly broken away and in section to disclose details;

Figure 4 is a sectional view on the line 4—4 of Figure 3;

Figure 5 is a fragmentary vertical sectional view through the window frame showing the lower sash in closed position;

Figure 6 is a detail sectional view taken on the line 6—6 of Figure 3;

Figure 7 is a view in front elevation of a fragmentary portion of the window sash and closure plate, and

Figure 8 is a sectional view taken on the plane indicated by the line 8—8 of Figure 3.

Like reference characters designate like or similar parts in the different views. 60

To facilitate an understanding of the invention, a window has been conventionally and fragmentarily shown of which A designates the sill, B the stiles rising therefrom, C the stop strips fastened to said stiles, D a 65 vertically slidable lower sash and E the stool.

In reducing the invention to practice, a suitable casing, preferably metallic is provided as at 10 and adapted for vertical disposition at one side of the window in contact with the stile at said side and with its ends engaging the sill A and lower edge of the sash D, respectively. 70

Casing 10 consists of a hollow shell 11 75 provided with a vertical slot or opening 12 at one side thereof through which a flexible metallic or other screen 13 travels. Adjacent the slot 12, the shell 11 has a substantially straight wall 14 which is adapted for 80 intimate contact against the inner edge of the stool E. At the ends of the shell, caps 15 and 16 are provided and at least one of them is detachable or removable and for instance the cap 16. To this end, cap 16 has 85 a depending rim 17 to encircle the exterior of shell 11 and which is provided with inwardly pressed lugs at 18 adapted to snap into openings 19 provided in the shell. The cap 16 being of metal, has certain resiliency 90 which permits yielding or snapping of the lugs 18. Each cap 15 and 16 has an inwardly extending sleeve or trunnion 20 and 21, respectively, integral with them which are exteriorly cylindrical or round and extend 95 through end plates 22 and 23 of a roller 24 which is journaled or rotatably mounted thereby. The screen 13 at its inner end as at 25 is fastened to the roller.

A spindle 26 is disposed longitudinally of the roller in a recess 27, with the inner end of the spindle which is round, located in a recess 28 in extension of recess 27 and which is of such size as to permit the spindle to slide therein longitudinally of the roller. 100 The outer end of spindle 26 is square or non-circular as at 29 and normally occupies a similarly shaped non-circular bore 30 provided through the sleeve 21. A shoulder 31 is provided on the spindle to engage the inner end of sleeve 21 and thus prevent outward displacement of the spindle. Within 105 110

the recess 27 and surrounding the spindle 26 is a contractile coil spring 32 having one end fastened as at 33 to the roller 24 and its other end fastened as at 34 to the spindle 26. Spring 32 is tensioned so as to urge winding movement of the roller 24 in order to wrap the screen 13 about it and urge the screen into the casing.

A key 35 is utilized having a square end 36 adapted to fit a square recess 37 in the portion 29. With the key 35 so positioned, it may be pushed toward the cap 16 which will dislodge the end 29 from recess 30 whereupon the key 35 may be turned in order to tension said spring 32. Thereafter with the portion 29 alined with recess or bore 30, and spindle 26 relieved of inward pressure, said spring 32 will reengage portion 29 in the bore 30. Key 35 is normally disengaged with end 36.

In order that the casing may be held in place against accidental displacement, each of the caps 15 and 16 has an outwardly and longitudinally struck securing spur 38, preferably sharpened, and designed to penetrate the sill A and the other to penetrate the sill B. Such penetration may be readily effected by moving the sash D downwardly against the uppermost spur 38. In this position, any tendency of the casing to turn is counteracted by the wall 14.

The free edge of the screen 13 is suitably reinforced or rigidified and provided with means to maintain it in position across the window space counter to the action of spring 32. To this end, an end strip substantially of U-shape is provided at 39, preferably from sheet metal, adapted to receive the free edge of screen 13 between the portions of the strip and be secured thereto by rivets or equivalent means as at 40. One side of the strip is struck outwardly in order to provide barrels 41 longitudinally thereof in which securing bolts 42 are slidably disposed. At the outer end, said bolts 42 terminate in securing spurs 43, preferably sharpened, and one adapted to penetrate the window sill A while the other is adapted to penetrate the lower edge of the sash D. The inner ends of bolts 42 are angular or inwardly offset to provide grips 44 which extend through elongated slots 45 provided in strips 39. The movement of the bolts 32 is thus limited by the engagement of the grips 44 with slots 45. An expansive coil spring 46 is housed within the strip 39 so as to bear at opposite ends against the grip 44 and thus urge projection of the bolts 42. The grips 44 however may be engaged by the fingers and moved toward each other against the tension of springs 45 in order to retract the bolts 42 which is essential during winding or unwinding of the screen 13.

The casing may normally be out of op-

erative position in the window. It may be readily brought into operative position by disposing the casing 10 as shown in Figure 1, causing the spurs 38 to penetrate the sill A and sash B and with the grips 44 engaged so as to retract and hold the bolts 42 retracted, the screen 13 may be unwrapped to the extent necessary to cause the free edge of strip 39 to abut the opposite stile B at which time the grips 44 are released so that the springs 45 will project them and move the spurs 43 one into engagement with the sill A and the other into engagement with the sash B. It will be noted that the lower edge of the screen 13 is disposed relatively close to the inner edge of the stool E thus effectively closing the window at this point against the entrance of insects. The spurs 43 hold the screen 13 open in the position shown in Figure 1 against the tension of spring 32, whereby it will be maintained taut. If desired, the casing 10 may be used merely as a prop for the window as when it is of the weightless type. Also if the space normally covered by the screen 13 is desired to be exposed, the grips 44 may be moved relatively so as to retract bolt 42 and thus permit the spring 32 to wind the screen within the casing.

Due to the fact that the sash D in actual practice is usually provided with an inclined lower edge and engages the cap 16, a slight space is presented between the upper edge of screen 13 and the lower edge of sash D. In order to close this space, I provide a strip or plate 47, preferably of metal, which is fastened against the inner surface of the sash D by screws or studs 48 passing through vertically elongated slots 49 in plate 47. Thus plate 47 normally extends 100 a distance below the lower edge of sash D in order to close the space mentioned. Plate 47 also has an outwardly extending flange 50 at its lower edge so as to more intimately engage the screen 13. If the casing 10 is not in place, the plate 47 does not have to be removed since when the sash in its lower position as shown in Figure 5, the plate will move upwardly due to the slot 49, to accommodate closing of said sash D. In such position the plate 47 will be located between sash D and the inner edge of stool E with the flange 50 intermediate the sill and the sash B, in effect serving as a weather strip.

Various changes within the details may be resorted to provided they fall within the spirit and scope of the invention.

What I claim as my invention is:

1. A roller device of the class described having a spindle, a roller, a winding spring for the roller securing the spindle to the roller, means engaged by the spindle normally preventing rotation thereof in both directions, said spindle being slidable to disengage said means to permit winding

thereof to vary the tension of said spring, and said spring serving to normally maintain said spindle in engagement with said means.

- 5 2. A roller device of the class described including a casing having an end provided with an inwardly extending trunnion, a roller within the casing journaled on the trunnion, said trunnion having a square 10 slot, a spindle within the roller having a square portion engaging said slot and a shoulder engaging said trunnion, a winding spring for the roller secured to the roller and to the spindle, said spindle being slideable to disengage said slot whereby the spindle may be turned to vary the tension of 15 said spring, said spindle being round at its inner end, the roller having a recess to journal said inner end and elongated to provide

clearance for sliding movement of the spindle, and said spring normally maintaining said square portion in said recess.

3. A roller window screen including a casing provided at one end with an angular opening, a roller journaled within the casing, a spindle mounted within the roller for endwise and rotary movements with respect thereto and having an angular outer end entering said opening, and a spring connected to the spindle and roller and yieldingly retaining the angular end of the spindle within said opening.

In testimony whereof I affix my signature in presence of two witnesses.
